UNITED STATES PATENT OFFICE.

CARLO ISIDOR, OF ROME, ITALY.

VEHICLE WITH CELLULAR PARTITIONS, BOXES, OR DRAWERS WHICH ARE LET SEPARATELY FOR THE CONVEYANCE OF GOODS.

1,072,948.

Specification of Letters Patent.

Patented Sept. 9, 1913.

Application filed January 7, 1913. Serial No. 740,652.

To all whom it may concern:

Be it known that I, CARLO ISIDOR, station-master, a subject of the King of Italy, residing at Rome, in the Kingdom of Italy, 5 have invented a new and useful Vehicle with Cellular Partitions, Boxes, or Drawers Which are Let Separately for the Conveyance of Goods, of which the following is a specification.

10 The present invention has sprung up from the idea of calling into being a new system of forwarding goods, consisting in causing to circulate vehicles with a certain number of boxes which by the charter are 15 let to the public. The users may hire the boxes even for a determined space of time and, having regard to the route, which the vehicle is designed to make, they may place in them the goods to be forwarded, where- 20 upon the user himself can shut up the box by means of any secret lock of his own. The different consignees, who previously have been acquainted with the way of opening the secret lock, upon producing the hire 25 ticket bearing the number of the box, are allowed access to the vehicle and may take possession of the goods contained in the hired box.

The chief aim of this new system of for- 30 warding goods is that of eliminating for the hirer the inconveniences arising in the case of ordinary transports by reason of the necessity of writing out the bills of freight, by reason of the delivery, of the 35 reception &c. Consequently, great losses of time as well as the expenses incurred in connection with the packing and fitting up the parcels and packages to be dispatched are avoided. Further advantages arise for 40 the hirer in that the boxes are merely accessible to the registered dispatcher and con- signee, and that the time of arrival of the 45 matters to be forwarded may be exactly determined in advance.

45 In the annexed drawing is represented by way of example a vehicle with cellular partitions according to the present invention. There are provided three scaffolds, namely two lateral ones and a central one, 50 which are parallel to the longitudinal axis of the vehicle. Each scaffold is formed of several series of boxes partitioned in cells having like or variable sizes. The scaffolds may either be made of structural iron 55 lagged with sheet iron, so as to form real

immovable boxes provided with covers and secret locks, or they may consist of simple frames of structural iron suitable to take up movable boxes or drawers which at will may be fastened by the aid of strong closing 60 means provided with secret locks; but the said scaffolds may also merely consist of sheet iron plates riveted or soldered, or lastly they may be made of any other material suitable for forming a cellular parti- 65 tion for stationary boxes or drawers.

In the annexed drawing is represented a vehicle having at one of its ends a platform —a— which by means of a sliding or a leaved door —b— communicates with the 70 interior —c— of the vehicle, where on the right, on the left and in the center are disposed the scaffolds —d—.

Figure 1 represents a longitudinal sec- 75 tion of the body of the vehicle taken on line 1—1 of Fig. 2. Fig. 2 is a horizontal sec- tion taken on line 2—2 of Fig. 1, and Fig. 3 is a cross section on the x—x of Fig. 2.

The scaffolds *d* are formed of several 80 series of boxes *e*₁, *e*₂, *e*₃, superposing each other, made of any suitable material, and each provided with independent locking 85 means accessible only through the door *b* leading into the compartment. Scaffolds *d* are also formed of a plurality of superposed 90 cells *f*₁, *f*₂, *f*₃ . . . formed of any suitable material and disposed near the sides and in the center of the compartment of the vehicle. The cells are provided with openings 95 accessible from the interior of the compart- ment only, through the door *b*. The cells may be formed with separating walls or by bars crossing each other and constituting a framework, so that boxes of different sizes, smaller than the cell, could be placed in them.

The opening of the cells and of the boxes in which the goods are placed, as well as the opening of the compartment in which may be stored boxes or vessels of any kind, can 100 be accomplished solely by the sender of articles or by the receiver, since only these parties are supposed to be in possession of the opening means. The conductor or op- erator of the vehicle can enter the same and 105 allow the interested parties to enter in too, but he can neither open the compartment or take out the goods or the vessels.

Claim—

A vehicle for the direct transmission of 110

goods from sender to receiver, having a compartment, a plurality of boxes or cells formed within the compartment of the vehicle, and each of which is provided with a lock whereby it may be controlled only both by the sender and the receiver of the articles which it contains, to the exclusion of the conductor or operator of the vehicle.

In testimony whereof I affix my signature in the presence of two subscribing witnesses. Rome this 23rd day of December, 1912.

CARLO ISIDOR.
